CLOSURE FOR RECEPTACLES

Charles S. Baron, Tiffin, Ohio

Application July 7, 1937, Serial No. 152,460

20 Claims. (Cl. 65—31)

The present invention relates to an improved cap and lid structure for receptacles such as syrup pitchers, sugar jars and containers for various other liquid and solid substances.

An essential feature of the invention consists in associating with a receptacle, a removable cap or closure having a discharge opening in its top, and providing a flap or lid normally positioned to close said opening, said flap being operable by a displaceable member or lever which extends into the cap and is operatively associated with the flap to move the same relative to the discharge opening in order to control the withdrawal from the receptacle of any desired portion of its contents.

A further object consists in providing the displaceable member with a depending handle which has the dual function of not only constituting means for lifting and tilting the receptacle to which the cap is applied, but also controls the position of the flap relative to the discharge opening, so that when the receptacle is supported in its normal position on a table, shelf or the like, and the handle is grasped to tilt the receptacle, the flap is automatically actuated to be moved away from the pouring opening to permit the withdrawal of the contents of the receptacle therefrom. Conversely, upon the receptacle being returned to its normal position and the handle released, the flap is returned to its normal position, thus providing simple, efficient and sanitary means for effecting the control of the discharge of the material from the receptacle upon the lifting and tilting of the same.

Other objects and advantages of the invention will become apparent from the following description when taken in conjunction with the accompanying claims and drawings.

Referring to the drawings in which are shown several preferred embodiments, the invention may assume:

Figure 1 is a side view of a receptacle with my improved cap applied thereto and showing parts in section for purpose of clearness of illustration, and also shows in dotted lines parts of the cap in their raised position.

Figure 2 is a plan view of Figure 1.

Figure 3 is a sectional view taken substantially along the line 3—3 of Figure 1.

Figure 4 is a disassembled perspective view of the flap and its control member.

Figure 5 is a view similar to Figure 1 of a modified form of the invention.

Figure 6 is a plan view of Figure 5.

Figure 8 is a sectional view of a modified form of cap structure.

Figure 9 is a transverse sectional view of Figure 8.

Figure 10 is a detail perspective view of the flap showing its connection to the control member as disclosed in Figure 8.

Figure 11 is a sectional view of another form of the invention.

Figure 12 is a sectional view taken along the line 12—12 of Figure 11.

Figure 13 is a view similar to Figure 1 showing another modification of the invention.

Figure 14 is a sectional view taken along the lines 14—14 of Figure 13.

Figure 15 is a sectional view of a further modification.

Figure 16 is a plan view of Figure 15.

Figure 17 is a vertical sectional view of another form of a receptacle closure and,

Figure 18 is a transverse sectional view of Figure 17.

Referring to the drawings in which like numerals indicate like parts in the several views, 10 designates a dispensing receptacle such as a 25 glass pitcher, jar or the like, and which may be of any desired shape and material for receiving syrup, sugar and various other solid and liquid substances so as to constitute a readily portable and sanitary container therefor. The receptacle 30 10 may have an externally threaded neck 11 for receiving the threaded skirt portion 12 of a metallic cap or closure 13. The top 14 of the cap has a discharge opening 15 through which the contents of the receptacle may be extracted or 35 withdrawn.

In order to provide a clean, neat, sanitary and efficient closure for the opening 15, the cap 13 has associated therewith a flap or lid 16 which is normally positioned to rest on the top 14 and 40 overlaps the opening 15 to close the same. The flap 16 is formed with a downwardly offset or bent portion 17 which terminates in an outwardly extending portion 18 that may be positioned in a plane substantially parallel to the plane 45 of the flap 16. Adjacent the juncture of the flap 16 with the bent portion 17, there are formed laterally extending ears or lugs 19. The top 14 is provided with a transverse slot or opening 20 through which loosely extends the offset portion 40 17 and the portion 18 of the flap so that the latter will normally be positioned beneath the top 14 and in a plane substantially parallel therewith. The portion 17 is of such width as to loosely extend through the opening 20 while the ears 19 55

are wider than the width of the slot, to constitute means for limiting the movement of the flap into the slot when the parts are assembled. The side or skirt 12 of the cap adjacent the top 14 has a curved orifice or slot 21 through which loosely extends a displaceable control member or lever 22. The member 22 is arranged normally to assume a substantially horizontal position and rests on the lower wall or edge of the slot 21, and is sufficiently spaced from the upper wall of the slot to permit rocking or tilting movement of the same in a vertical plane. Depending from the inner end of the member 22 is a substantially U-shaped wire staple or rod 23 which has its end 24 extending through an elongated slot or perforation 25 in the portion 18 of the flap (Figure 3). The member 22 is connected outside of the cap to a depending handle 26 by the screw 27. As shown, the handle is preferably made of wood, but can be formed of bakelite or any other suitable, light and inexpensive durable material. If desired, the handle may be formed integral with the member 22 in the manner as shown in certain of the other forms hereinafter described.

For the purpose of illustration, assuming that the receptacle 10 is filled with syrup or molasses and is resting in its normal position on a table or shelf, it will be seen that upon grasping the handle 26 to lift and tilt the same to its pouring position, that the lever 22 is moved outwardly and upwardly and simultaneously therewith, the flap 16 is raised from its normal flat position over the opening 15 to its opened position by reason of the downward pressure exerted by the inner end of the lever 22 on the overlapped portion 18 of the flap, thus causing the bent portion 17 to swing upwardly about the wall of the opening 20 so that the latter constitutes a fulcrum support for the flap. At the same time, the portion 18 is swung downwardly within the cap and this movement is limited by reason of the engagement of the end of the wall of the slot 25 with the staple member 24. Thus, the staple coacts with the slot 25 to limit the raising movement of the cap relative to the opening 15, and also constitutes means for preventing the flap from dropping out of the cap due to its interlocking connection with a wall of the slot. The member 22 may have laterally extending opposed shoulders 28 engaging the inner wall of the skirt and which coact with a depending staple or retaining means 29 on the member 22 adjacent the outside of the skirt for preventing longitudinal sliding movement of the lever relative to the cap, when the parts are set up. When the handle is released, it automatically returns to its normal vertical position. Should the flap for any reason have a tendency not to return to its normal flat position, the staple 23 will engage the underside of the portion 18 so as to exert an upward pressure thereon which in turn will move the flap to its closed position. The rectangular slot or hole 25 reduces the weight of this end of the flap and makes the opposite end heavier so that the flap will close smoothly and quickly. The staple 29 also functions to act as a guard for the adjacent outer portion of the skirt to prevent the same from being dented or damaged during the handling of the cap.

The cap 13 may be provided with a reduced shoulder portion 30 which coacts with the mouth of the receptacle 10 for clamping therebetween, a liner 31 of suitable gasket material. Thus, when the receptacle is used as a container for syrup or molasses, the same may be initially

filled and when the cap is applied with the liner, a tight seal is formed which precludes the escape of the contents of the receptacle through the opening 15 irrespective of the position of the flap 16. The receptacles filled with syrup may be supplied to the wholesaler and retailer in this manner and when purchased by the consumer, the liner may readily be removed and the cap reapplied so that the syrup is now available for table use. When the parts are in their normal closed position, the portion 18 of the flap 16 and the overlapped end of the lever 22 are disposed substantially parallel and against each other, so as to be immediately operable upon the actuation of the handle.

In the form of the invention shown in Figure 5, the screw cap 32 is arranged to be connected to the neck 33 of a receptacle 34 such as a glass pitcher, jar or the like. The top 35 of the cap has a discharge opening 36 for dispensing the contents of the receptacle therefrom and may be initially cut off from the receptacle by a liner 37. A flap 38 positioned above the top 35 normally closes the opening 36 and has a depending offset portion 39 which extends through a slot 40 in the top. Laterally projecting lugs 41 extend outwardly from the flap 38 adjacent and above the slot 40 to limit the movement of the flap into the cap. The portion 39 has extending outwardly therefrom and beneath the top 35, a flat portion 42, the end of which is flanged downwardly as at 43. A control member or lever 44 extends through an opening 45 into the cap and has its inner end provided with depending spaced perforated ears 46 through which extends a transverse pin 47. The portion 42 of the flap is arranged to extend between the ears 46 and above the pin 47 so that the parts will normally assume the position shown in full lines in Figure 5. The member 44 may be provided with opposed shoulders 48 which engage the inner wall of the skirt of the cap and coact with a pin 49 that engages the outer wall of the skirt, to prevent sliding movement of the member relative to the cap. A combined lifting and operating handle 50 is suitably connected to the lever 44 or may if desired be integral therewith. Assuming that the parts are in their normal position and that the liner 37 has been previously removed from the receptacle, it will be seen upon grasping the handle 50 to raise and tilt the receptacle to its pouring position, that the flap 38 and the member 44 will assume their dotted line positions shown in Figure 5 and thus permit the discharge of the material through the opening 36. The raising movement of the flap 38 will be limited by reason of the engagement of the flange 43 with the pin 47. When the receptacle is returned to its normal position and the handle 50 released, the downward movement of the lever 44 will insure the return of the flap 38 to its closed position over the opening 36. As the flange 43 projects slightly below the pin 47, when the parts are in their normal position, the latter will act to prevent the flap 38 from being accidentally withdrawn from the cap since such outward movement would cause the flange 43 to be brought into abutting engagement with the pin 47.

In the form of the invention shown in Figure 8, the top 51 of the threaded cap 52 has a discharge opening 53 controlled by a flap or valve 54. This flap is provided with a depending offset or bent portion 55 which extends through a transverse slot 56 in the top 51. Lugs 57 on the flap are located above the slot 56 to constitute

means for limiting the inward movement of the flap. The bent portion 55 terminates in a pair of spaced fingers 58 which extend substantially parallel with the flap 54 and have depending 5 flanged ends 59. Coacting with the flap 54 is a control lever 60 which extends into the cap through a slot 61 and has its inner end provided with a medially disposed depending arm 62 arranged to fit within the space 63 between the 10 fingers 58 and terminates in laterally projecting arms or portions 64 adjacent the underside of the fingers 58 when the parts are set up. The lever 60 may have shoulder portions 65 which bear against the inner side of the cap and coact 15 with a pin 66 on the outside thereof for limiting the sliding movement of the lever relative to the cap. As shown, the lever 60 is bent downwardly as at 67 to form a depending integral handle 68. Manifestly, a wooden handle or the like 20 such as shown in the forms previously described, could be substituted for the handle 68. Normally, the parts assume the position shown in Figure 8 so that upon the grasping of the handle to lift and tilt the receptacle to which the cap 25 52 is applied to its pouring position, the movement of the handle will cause the raising of the flap 54 due to the engagement of the inner end of the member 60 with the top of the fingers 58 so as to lower the latter and raise the flap 54 30 about its fulcrum support, and thus will permit the free discharge of the contents of the receptacle through the opening 53. Upon the receptacle being returned to its normal position and the handle 68 being released, the latter together 35 with its associated parts will return to their vertical position and at the same time will act to return the flap 54 by virtue of the arms 64 being brought into engagement with the underside of the fingers 58. As the arms 64 are normally in 40 the path of the flanged ends 59, they will act to prevent the flap from dropping out of the cap. In the modified form disclosed in Figure 11, the top 69 of the threaded cap 70 has a discharge opening 71 which is controlled by a flap valve 45 or lid 72 having a bent portion 73 which extends through a transverse opening 74 in the top and is also provided with the laterally disposed ears 75 arranged to bear against the top adjacent the slot 74 to limit the inward movement of the flap. 50 The offset portion 73 terminates in the flat portion 76 positioned beneath the top and which extends substantially parallel with the flap 72. The end of the portion 76 is flared upwardly as at 77 and may carry a pin 78 which acts to prevent the flap from dropping out of the cap and becoming lost. A displaceable member 79 extends through a slot 80 in the side or skirt of the cap and has laterally disposed shoulders 81 which bear against the inner side of the cap and 55 coact with a pin 82 on the outer end of the member 79 to provide means for preventing sliding movement of the member relative to the cap when the parts are set up. The member 79 may be provided either with an integral handle 83 or be detachably connected to a separate handle piece as disclosed in Figures 1 and 5. The bent portion 73 of the flap coacts with the adjacent wall of the slot 74 so that the latter constitutes a fulcrum support for the flap when the same 60 is moved relative to the opening 71. Upon the grasping of the handle 83 to raise and tilt the receptacle to which the cap is applied to its pouring portion, the inner end of the member 79 is depressed and bears against the portion 76 of the flap with the result that the flap is moved 65 about its fulcrum support away from the opening 71 to permit the discharge of the contents of the receptacle therefrom. When the receptacle is returned to its normal position, and the handle is released, the flap 71 falls by gravity to its closed position and the handle and its associated parts move to the position shown in Figure 11. This form of the invention essentially distinguishes from the forms previously described in that in the other forms positive means 10 are employed to return the flap to its normally closed position while in the form shown in Figure 11, the flap is arranged to be returned by gravity and is only operable by the handle 83 15 to be raised.

In the form thus far described, it will be seen that upon the handle being grasped to move the receptacle to its pouring position, that the flap is simultaneously operated through its connection with the handle and is raised relative to the 20 discharge opening to permit the withdrawal of any desired portion of the contents of the receptacle. Thus, the use of weighted balance members for actuating the flap are dispensed with and the number of essential parts is reduced to a 25 minimum so that the cap may be economically manufactured without danger of impairing its efficiency and durability.

In the modified form of the invention shown in Figure 13, a receptacle such as a glass jar, 30 pitcher or the like 84 has a handle 85 and is provided with an externally threaded neck 86. Associated with the neck, is a threaded collar or skirt 87 of a two-piece metallic cap 88. The collar 87 is formed with an inwardly extending 35 annular flange 89 which engages a complementary flange 90 on the upper section 91 of the cap so that when the collar 87 is applied to the receptacle, the section 91 is maintained firmly in 40 position. A liner 92 of any suitable gasket material is interposed between the mouth of the receptacle and the flange 90 to provide a hermetical seal at the mouth of the receptacle when the cap is connected thereto. The upper section 91 has its top 93 provided with a pouring 45 opening 94 which is controlled by a flap or lid 95 having a depending offset portion 96 which extends through a transverse slot 97 in the top. Spaced protuberances 98 extend laterally from 50 opposed sides of the flap adjacent and above the slot 97 to limit the inward movement of the flap. It will be seen that the side wall of the slot 97 constitutes a fulcrum support about which the flap may be swung relative to the opening 94. The portion 96 of the flap has an angular 55 portion 99 extending therefrom which is provided with an elongated transverse opening 100. A displaceable member in the form of a thumb-piece 101 extends outwardly from the top of the cap and has a depending portion 102 provided 60 with a medially reduced end 103. The portion 102 extends through a slot 104 in the top, and the reduced end 103 through the opening 100. The member 101 is secured to the flap by a pin 105 which engages the underside of the portion 65 99 beneath the opening 100. The connection of the thumb-piece 101 with the flap 95 not only provides means for raising the flap upon the depressing of the thumb-piece, but also precludes the flap from being withdrawn from the cap. 70 The thumb-piece 101 is conveniently positioned adjacent the handle 85 so that when the handle is grasped to raise and tilt the pitcher, the thumb or forefinger may be used to depress the thumb-piece 101 to raise the flap relative to the open- 75

ing 94. When the receptacle is initially filled, the liner 92 is applied to the mouth thereof and the cap is then connected to the neck to provide a tight seal to preclude the escape of the 5 contents therefrom. Thus, it will be seen that the receptacles may be filled at the factory and sold by the wholesaler or retailer in the form which they are received and when purchased by the user, it will merely be necessary to 10 remove the cap to withdraw the liner 92 and then reapply the cap to render the receptacle available for table use.

In the modified form of the invention disclosed in Figure 15, a two-piece cap or closure 15 106 having a threaded collar or lower section 107 and an upper section 108, is arranged to be detachably connected to any suitable receptacle in a manner similar to the cap 88 previously described. The top 109 of the cap 106 has a discharge opening 110 controlled by a flap 111. The 20 flap 111 is formed with a depending offset portion 112 which is bent upwardly as at 114 to provide a portion 115 which extends through a slot 116 in the top 109. The end of the portion 25 115 terminates in a thumb-piece 117 which extends outwardly above the top and is arranged to be positioned above the handle 85 of the receptacle when the cap is applied. In other words, the flap 109 and the thumb-piece 117 are made 30 on one piece and are so associated through the spaced slots 113 and 116 as to constitute a simple, efficient and inexpensive means for controlling the discharge of the contents of the receptacle through the opening 110. Preferably, the 35 flap 111 is wider than the bent portion 112 so as to provide the shoulders 118 adjacent and above the slot 113 to constitute a stop for insuring the flap being maintained at all times in proper position relative to the opening 110. The 40 bent portion 112 coacts with the portion 115 to provide means for retaining the flap on the cap while the thumb-piece 117 when depressed, is brought into engagement with the adjacent wall of the top so as to limit the raising movement of the flap 111 relative to the opening 110. Sufficient clearance is provided between the slot 45 113 and the angular portion 112 of the flap to permit the wall of the slot 113 to constitute a fulcrum support about which the flap is moved to 50 its opened and closed positions.

In the modified form of the invention shown in Figures 17 and 18, the receptacle closure or cap 118 may have a lower externally threaded skirt 119 so as to be detachably connected to 55 a receptacle to which the cap is to be applied, and is also provided with a reduced, smooth, upper annular portion 120 which is connected to the skirt 119 by a shoulder 121. The shoulder 121 is arranged to coact with the mouth of the 60 receptacle for initially clamping a liner such as shown in Figure 1 to the receptacle. The top 122 of the cap has a pouring opening 123 controlled by a flap 124. This flap is formed with a downwardly offset or bent portion 125 which 65 extends through a transverse slot 126 in the top and terminates in a reduced angularly disposed flat portion 127. The outer end of which has a medially disposed reduced flange 128 extending downwardly therefrom. The offset portion 70 125 of the flap loosely extends through the slot 126 so that the wall of the latter constitutes a fulcrum support for the flap to permit the same to be moved relative to the opening 123. The flap above the top 122 and adjacent the slot 126 75 may be provided with laterally projecting shoul-

ders 129 which limit the movement of the flap inwardly relative to the cap. The flap is also provided beneath the top with upwardly bent ears or beads 130 cut out or formed from the sides of the portion 127 so that these ears when 5 bent upwardly constitute retaining means positioned beneath the top to prevent the flap from sliding outwardly through the slot 126 and act to insure the flap being maintained at all times in its proper position relative to the discharge 10 opening 123.

Extending through a curved slot or orifice 131 in the smooth side 120 of the cap, is a displaceable member or lever 132. The inner or short end of which is positioned beneath the top and above 15 the portion 127 of the flap and is provided with a depending flange 133 having a transverse opening 134 through which loosely extends the flat portion 127 of the flap. The lever 132 is rockably or tiltably mounted on the lower wall 20 of the slot 131 so that the outer end normally assumes a horizontal position as shown in Figure 17. Thus, it will be seen that when the outer or long end of the lever 132 is moved upwardly from its normal horizontal position, that 25 it will impart a downward movement to the inner end of the lever to bring the same into engagement with the portion 127 of the flap thus causing both of these parts to be moved downwardly during the further upward movement of 30 the outer end of the lever. This movement causes the flap 124 to swing about its fulcrum support and be raised relative to the discharge opening 123 to permit the discharge of the contents of the receptacle to which the cap is applied when the latter is tilted to its pouring position.

In order to prevent the lever 132 from sliding axially relative to the cap, it is preferably formed with spaced curved shoulders 135 which engage the inner wall of the smooth portion 120 of the 40 cap. Coacting with the shoulders 135 is a plate 136 riveted or otherwise secured as at 137 to the underside of the lever 132 and having a depending curved flange 138 at its inner end which engages the adjacent outer side of the cap, so 45 as movably to secure the lever to the cap. The flange 138 is also arranged to be brought into abutting engagement with the outer wall of the cap to limit its downward movement and to maintain the same in its normal horizontal 50 position.

Thus, it will be seen that the ears 130 coact with the shoulder portion 129 to retain the flap in proper position relative to the cap and that the shoulders 135 coact with the stop 138 to 55 insure the lever 132 being retained in its desired position. When the flap is raised to its extreme position by the actuation of the lever 132, the flange 128 will be moved into abutting engagement with the flange 133, to limit the 60 raising of the flap. When the lever is returned to its normal position, the stop 138 will bear against the side of the cap to limit its downward movement. The outer end of the lever 132 may be connected to a depending operating handle 65 (not shown) in the manner as disclosed in Figure 1 or may have its end portion bent downwardly to provide an integral handle.

Thus, it will be seen that in the several forms of the invention shown and described, that the 70 discharge opening in the cap is controlled by a flap which is normally positioned to close the opening, and that the cap is provided with spaced slots which as shown in Figures 1 to 12, 17 and 18 have one of the slots in the top and the other 75

in the side or skirt of the cap while in Figures 13 to 16, both of these spaced slots are formed in the top. It will also be noted, that one of these slots coacts with the bent portion of the flap to constitute a fulcrum support about which the flap is swung relative to the discharge opening. Further, manually operable means in the form of a displaceable or rockable member is connected to the flap to actuate the same, which 10 means may have a handle that performs the dual function of lifting and tilting the receptacle to which the cap is applied, and simultaneously therewith, raises the flap relative to the discharge opening. Moreover, when the receptacle is re- 15 turned to its normal position and the handle released, the return movement of the handle insures the flap being moved to close the discharge opening. The handle if desired, may be formed integral with the receptacle and the displaceable 20 or rockable means may be positioned adjacent the handle so as to be conveniently actuated to raise the flap when the receptacle is tilted to its pouring position.

It is to be understood that the forms of the 25 invention shown and described are merely illustrative of preferred embodiments and that such changes may be made as fall within the purview of one skilled in the art without departing from the spirit of the invention.

30 I claim:

1. A cap for receptacles having spaced slots and provided with a discharge opening in the top thereof, a flap above the top and normally positioned to close said opening, said flap having 35 a depending offset portion extending through one of said slots, said offset portion loosely engaging the wall of the slot so that the latter constitutes a fulcrum support for the flap when the same is moved relative to said opening, and 40 a movable member extending through the other of said slots and operatively associated with said offset portion, whereby upon the actuation of said member to raise the flap relative to said opening about its fulcrum support.

45 2. A cap for dispensing receptacles having spaced slots and provided with a discharge opening in the top thereof, a flap above the top and normally positioned to close said opening, said flap having a depending offset portion extending 50 through one of said slots, said offset portion loosely engaging the wall of the slot so that the latter constitutes a fulcrum support for the flap when the same is moved relative to said opening, a displaceable member extending through the other of said slots and operatively associated 55 with said offset portion, whereby upon the actuation of said member to raise the flap relative to said opening about its fulcrum support, and 60 means for limiting the sliding movement of said member relative to said cap.

65 3. A cap for dispensing receptacles having spaced slots and provided with a discharge opening in the top thereof, a flap above the top and normally positioned to close said opening, said flap having a depending offset portion extending 70 through one of said slots, said offset portion loosely engaging the wall of the slot so that the latter constitutes a fulcrum support for the flap when the same is moved relative to said opening, means for preventing the withdrawal of the flap from the cap, and a movable member extending through the other of said slots and operatively associated with said offset portion, whereby upon the actuation of said member to raise 75

the flap relative to said opening about its fulcrum support.

4. A cap for dispensing receptacles having spaced slots and provided with a discharge opening in the top thereof, a flap above the top and normally positioned to close said opening, said flap having a depending offset portion extending through one of said slots, said offset portion loosely engaging the wall of the slot so that the latter constitutes a fulcrum support for the flap 10 when the same is moved relative to said opening, means for preventing the withdrawal of the flap from the cap, a movable member extending through the other of said slots and operatively associated with said offset portion, whereby upon 15 the actuation of said member to raise the flap relative to said opening about its fulcrum support, and means for limiting the sliding movement of said member relative to said cap.

5. A cap for dispensing receptacles having a 20 discharge opening in its top and provided with spaced slots, a flap above the top and normally positioned to close said opening, said flap having a depending portion extending through one 25 of said slots, said portion terminating in an angularly disposed portion beneath the top, said depending portion loosely engaging the side wall of the slot so that the latter provides a fulcrum support for the flap when it is moved relative to said opening, a displaceable member extending 30 through the other of said slots, and means operatively connecting said member to the angular portion of the flap whereby upon the actuation of the member to raise the flap relative to said opening about its fulcrum support. 35

6. A cap for dispensing receptacles having a discharge opening and a slot in the top thereof, a flap above the top and normally positioned to close said opening, said flap having an offset portion extending through said slot, said offset 40 portion loosely engaging a wall of the slot so that the latter provides a fulcrum support for the flap when it is moved relative to said opening, said cap having an orifice in the side thereof, a movable member extending into the cap 45 through said orifice, and means operatively connecting the inner end of said member to the offset portion beneath the top whereby upon the actuation of said member to raise the flap relative to said opening about its fulcrum support.

7. A cap for dispensing receptacles having a 50 discharge opening and a slot in the top thereof, a flap above the top and normally positioned to close said opening, said flap having an offset portion extending through said slot, said offset portion loosely engaging a wall of the slot so 55 that the latter provides a fulcrum support for the flap when it is moved relative to said opening, said cap having an orifice in the side thereof, a movable member extending into the cap through said orifice, means operatively connecting the inner end of said member to the flap, and a handle connected to the outer end of said member for effecting the actuation of the flap whereby upon the grasping of the handle to tilt the cap to its pouring position, to move the flap 60 away from said opening. 65

8. A cap for dispensing receptacles having a discharge opening and a slot in the top thereof, a flap above the top and normally positioned to close said opening, said flap having a bent portion extending through said slot and terminating in an angularly disposed portion beneath the top, said bent portion loosely engaging the wall of the slot so that the latter provides a fulcrum support for the flap when it is moved relative to 70 75

said opening, said cap having an orifice in the side thereof, and a rockable member extending through said orifice and overlapping the angular portion of the flap, said member being disposed above the angular portion and arranged when actuated to raise the flap relative to said opening.

9. A cap for dispensing receptacles having a discharge opening and a slot in the top thereof, a flap above the top normally positioned to close said opening, said flap having an offset portion extending through said slot and terminating in an angularly disposed portion beneath the top, said offset portion engaging the side wall of the slot so that the latter provides a fulcrum support for the flap when it is moved relative to said opening, said angular portion of the flap having a slot therein, the side wall of the cap adjacent the top having an orifice, and a displaceable member having a depending handle disposed outside of the cap, said member extending into the cap through said orifice and provided with a depending staple having one end extending through the slot in the angular portion of the flap to prevent the withdrawal of the flap from the cap, said staple also acting to limit the outward movement of the flap relative to said opening whereby upon the grasping of the handle to tilt the cap to its pouring position, to move the flap away from said opening.

10. A cap for dispensing receptacles having a discharge opening and a slot in the top thereof, a flap above the top normally positioned to close said opening, said flap having an offset portion extending through said slot and terminating in an angularly disposed portion having a flanged end, said offset portion loosely engaging the wall of the slot so that the latter provides a fulcrum support for the flap when it is moved relative to said opening, said cap having an orifice in the side thereof adjacent the top, a displaceable member extending through said orifice, said member having spaced depending lugs connected by a transverse pin, the offset portion of said flap extending between said lugs and above said pin to provide means for preventing withdrawal of the cap from the flap and to limit the raising of the flap relative to said opening, and a handle connected to said member whereby upon the grasping of the handle to raise and tilt the cap to its pouring position, to move the flap away from said opening.

11. A cap for dispensing receptacles having a discharge opening and a slot in the top thereof, a flap above the top and normally positioned to close said opening, said flap having a bent portion extending through said slot and terminating in spaced angularly disposed fingers positioned beneath the top, said bent portion loosely engaging the wall of the slot so that the latter provides a fulcrum support for the flap when it is moved relative to the latter, said cap having an orifice in the side thereof adjacent the top, a control lever extending through said orifices and having at its inner end, a depending arm arranged to fit between said fingers and having outwardly projecting portions arranged to engage the fingers whereby to effect movement of the flap relative to the opening upon the actuation of said lever.

12. In combination with a receptacle having an externally threaded neck, a cap having a threaded skirt and a reduced smooth portion above the skirt, said reduced portion being connected to the skirt by an inwardly disposed shoulder, a liner arranged initially to close the mouth of the

receptacle and be clamped thereto by the shoulder when the threaded skirt of the cap is applied to the neck, said cap having a discharge opening and a slot in the top thereof, a flap above the top normally positioned to close said opening, said flap having an offset portion extending through said slot and terminating in an angularly disposed portion below the top, said offset portion loosely engaging the wall of the slot so that the latter constitutes a fulcrum support for the flap when it is moved relative to said opening, said cap having an orifice in the side thereof adjacent the top, a displaceable member extending through said orifice and having its inner end positioned above and overlapping the inner portion of said flap, and a handle connected to the displaceable member outside of the receptacle whereby when the liner is removed and the cap is reapplied to the receptacle and the handle lifted to raise the same to its pouring position, to automatically raise the flap relative to said opening.

13. In combination with a receptacle having an externally threaded neck, a cap having a threaded skirt arranged to be detachably connected to said neck, said cap having a discharge opening and a slot in the top thereof, a flap above the top normally positioned to close said opening, said flap having an offset portion extending through said slot and terminating in an angularly disposed portion below the top, said offset portion loosely engaging the wall of the slot so that the latter provides a fulcrum support for the flap when it is moved relative to said opening, said cap having an orifice in the side thereof adjacent the top, a rockable member extending through said orifice and having its inner end positioned above and overlapping the angular portion of said flap whereby upon the actuation of said member to raise the flap relative to said opening, means for limiting the sliding movement of the flap relative to said cap, and means for preventing the withdrawal of the flap from the cap.

14. A cap for dispensing receptacles having a discharge opening and spaced slots in the top thereof, a flap above the top and normally positioned to close said opening, said flap having a depending offset portion extending through one of said slots and arranged loosely to engage the wall thereof to provide a fulcrum support for the flap when the same is moved relative to said opening, and means extending through the other of said slots and operatively connected to said offset portion whereby upon the actuation of said means to raise the flap relative to said opening.

15. A cap for dispensing receptacles having a discharge opening and spaced slots in the top thereof, a flap above the top and normally positioned to close said opening, said flap having a depending offset portion extending through one of said slots and arranged loosely to engage the wall thereof to provide a fulcrum support for the flap when the same is moved relative to said opening, a displaceable member extending through the other of said slots, and means pivotally connecting the displaceable member to said offset portion beneath the top whereby upon the actuation of said member to raise the flap relative to said opening, said member when released, acting to return the flap to its normally closed position.

16. In combination with a receptacle, a cap arranged to be detachably connected thereto, said cap having a discharge opening and a slot in the top thereof, a flap above the top normally positioned to close said opening, said flap having an

offset portion extending through said slot and terminating in an angular disposed portion, said offset portion loosely engaging the wall of the slot so that the latter provides a fulcrum support for the flap when the same is moved relatively to said opening, said cap having an orifice in the side thereof, a displaceable member extending through said orifice and overlapping said offset portion, and a handle connected to said member whereby upon the grasping of the handle and the tilting of the receptacle to its pouring position to effect the raising of the flap, and automatically to close the flap when the handle is released.

17. In combination with a receptacle having an externally threaded neck, a cap having a threaded skirt arranged to be detachably connected to said neck, said cap having a discharge opening and a slot in the top thereof, a flap above the top normally positioned to close said opening, said flap having an offset portion extending through said slot and terminating in an angularly disposed portion below the top, said offset portion loosely engaging the wall of the slot so that the latter provides a fulcrum support for the flap when it is moved relative to said opening, said cap having an orifice in the side thereof adjacent the top, a displaceable member extending through said orifice, means operatively connecting said member to the angularly disposed portion of the flap, and a handle connected to said member whereby upon the grasping of the latter and the tilting of the receptacle to its pouring position to effect the raising of the flap and to close the flap upon the handle being released.

18. In combination with a receptacle having an externally threaded neck, a cap having a threaded skirt arranged to be detachably connected to said neck, said cap having a discharge opening and a slot in the top thereof, a flap above the top normally positioned to close said opening, said flap having an offset portion extending through said slot and terminating in an angularly disposed portion below the top, said offset portion loosely engaging the wall of the slot so that the latter provides a fulcrum support for the flap when it is moved relatively to said opening, said cap having an orifice in the side thereof adjacent the top, a displaceable member extending through said orifice, said member having its inner end overlapping the angular portion of the flap and provided with a depending staple, said angular portion having an elongated opening through which one end of the staple extends, and a handle connected to said member whereby upon the grasping of the latter and the tilting of the receptacle to its pouring position to raise the flap relative to said opening and to close the flap upon the receptacle

being returned to its normal position and the handle being released.

19. In combination with a receptacle having an externally threaded neck, a cap having a threaded skirt arranged to be detachably connected to said neck, said cap having a discharge opening and a slot in the top thereof, a flap above the top normally positioned to close said opening, said flap having an offset portion extending through said slot and terminating in an angularly disposed portion below the top, said angular portion terminating in a downwardly extending flange, said offset portion loosely engaging the wall of the slot so that the latter provides a fulcrum support for the flap when it is moved relatively to said opening, said cap having an orifice in the side thereof adjacent the top, a displaceable member extending through said orifice and provided adjacent its inner end with spaced depending perforated ears having a transverse pin extending therethrough, said angular portion arranged to extend between the ears and above said pin, and a handle connected to said member whereby upon the grasping of the handle and the tilting of the receptacle to its pouring position, simultaneously to raise the flap, said flap being limited in its upward movement by the engagement of the flange on the angular portion with said pin, said flap upon the receptacle being returned to its normal position and the handle released being automatically moved to close said opening.

20. A cap for dispensing receptacles having a discharge opening and a slot in the top thereof, a flap above the top and normally positioned to close said opening, said flap having a depending portion extending through said slot and terminating in a reduced outwardly projecting portion disposed beneath the top, said depending portion at the juncture of the reduced portion being formed with spaced upwardly extending ears arranged to engage the underside of the top to prevent the removal of the flap from the cap, said depending portion loosely engaging the wall of the slot so that the latter provides a fulcrum support for the flap when the same is moved relative to the discharge opening, said cap having an orifice in the side thereof, a rockable member extending through said orifice and over-lapping the reduced portion of the flap, said member having a depending slotted flange through which slidably extends the reduced portion of the flap, whereby upon the raising of the outer end of said member from its normal position to effect the raising of the flap relative to the discharge opening, and means on said member coacting with the cap for limiting the movement of said member.

CHARLES S. BARON.
